UNITED STATES PATENT OFFICE.

ADOLF HEPNER, OF MUNICH, GERMANY.

DESIGN FOR AN ASPARAGUS-HOLDER.

44,103.

Specification for Design.

Patented May 27, 1913.

Application filed November 30, 1912. Serial No. 734,399. Term of patent 14 years.

To all whom it may concern:

Be it known that I, ADOLF HEPNER, a citizen of the United States, residing at Munich, in Bavaria, Germany, have invented a new, original, and ornamental Design for an Asparagus-Holder, of which the following is a specification, reference being had to the accompanying drawing, forming part thereof.

The figure is a perspective view of an asparagus-holder, showing my new design.

I claim—

The ornamental design for an asparagus-holder, as shown.

ADOLF HEPNER.

Witnesses:

RICHARD LEMP,
JOHANNA STERN.
